UNITED STATES PATENT OFFICE

STEPHEN ERNEST MEYER, OF HAYDEN, ARIZONA

PISTON CONSTRUCTION

Application filed March 30, 1931, Serial No. 526,466. Renewed July 12, 1932.

This invention appertains to new and useful improvements in piston constructions especially adapted for use in internal combustion engines, compressors, vacuum pumps, and in fact other types of pumps and engines.

The principal object of this invention is to provide a piston with novel packing means which will be more efficient and durable than packing means now in use in this capacity.

10 Other important objects and advantages of the invention will become apparent to the reader of the following specification.

In the drawings:—

15 Figure 1 represents a side elevational view of the novel piston.

Fig. 2 represents a top plan view of the piston.

Fig. 3 represents a fragmentary side elevational view of the upper plate.

20 Fig. 4 represents a top plan view of one of the packing units.

Fig. 5 represents a side elevational view of one of the sections of one of the packing units.

25 Fig. 6 represents a fragmentary detailed sectional view through the assembled piston.

Fig. 7 represents a fragmentary perspective view of one of the packing unit sections.

Referring to the drawings wherein like numerals designate like parts, it can be seen that numeral 5 represents the usual apron portion of a piston which is provided with the closed head portion 6. Numeral 7 represents the usual connecting rod which is attached 30 to the piston in the usual conventional manner.

In further carrying out the invention, a pair of packing units denoted by numeral 8—8, are arranged upon the head 6 and upon 40 the packing units 8—8 and being smaller in diameter than the said packing unit is the clamp plate 9.

Now referring to Fig. 4, it can be seen that either one of the packing units 8 consists of 45 a pair of semi-circular sections 10—10, each constructed identically. At the straight edge portion of each section 10 is a notch 11 adjacent one end and a tongue 12 adjacent the opposite end, the tongues being engaged 50 in the notches 11 when the sections are as-

sembled together as in the manner shown in Fig. 4.

Each of the sections 10—10 is provided at its straight edge portion with a pair of rectangular cut-out portions or indentures 13—13 in each of which is a pair of teats 14—14 which act as guides for the adjacent ends of a pair of springs 15.

As can be clearly seen in Fig. 4, a notch 16 is provided in the straight edge portion 50 of each section 10 and between the cut-out portion 13—13, so that when the sections 10—10 are assembled, a square opening 17 is provided for the reception of the polygonal-shaped shank 18 which projects from 65 the head 19. This head 19 engages into a centrally located opening of the plate 9, and project openings 17 of the packing units 6—8. The shank 18 is provided with a threaded and reduced portion 20, which depends thru the head portion 6 of the piston 70 construction, and has a nut 21 engaged thereon for securing the plate 9 in position over one of these units 8—8, which are arranged, so that the sections 10 of the upper units are 75 disposed at right angles to the sections 10 of the lower units, and obviously the spring 15 tends to urge the sections outwardly to impinge against the wall of the cylinder in which the piston operates.

80 While the foregoing specification sets forth the invention in specific terms, it is to be understood that numerous changes in the shape, size and materials, may be resorted to without departing from the spirit and scope 85 of the invention as claimed hereinafter.

Having thus described my invention, what I claim as new is:—

1. A piston construction comprising a cylindrical body having an opening through 90 the top thereof, a disk constructed of a pair of semi-circular sections each section provided at its straight edge portion with indentures, compressible springs interposed between the sections and bearing into the indentures, said sections each being provided with projections in the indentures to engage into the corresponding end convolutions of the springs to prevent displacement thereof, the straight edge portions of the sections 95 100

being provided with inwardly extending polygonal shaped openings which register when the sections are assembled, and securing means provided with a polygonal portion for disposition through the polygonal shaped openings in the sections and through the said opening in the top of the piston body.

2. A piston construction comprising a cylindrical body having an opening through the top thereof, a disk constructed of a pair of semi-circular sections each section provided at its straight edge portion with indentures, compressible springs interposed between the sections and bearing into the indentures, said sections being each provided with projections in the indentures to engage into the corresponding end convolutions of the springs to prevent displacement thereof, the straight edge portions of the sections being provided with inwardly extending polygonal shaped openings which register when the sections are assembled, and securing means provided with a polygonal portion for disposition through the polygonal shaped openings in the sections and through the said opening in the top of the piston body, and tongue and notch connections between the sections at the straight edge portions thereof.

In testimony whereof I affix my signature.

STEPHEN ERNEST MEYER.
